UNITED STATES PATENT OFFICE.

GEORG FISCHER, OF NUEREMBERG, BAVARIA, GERMANY.

PLAY WITH ROTATING GIG.

SPECIFICATION forming part of Letters Patent No. 359,317, dated March 15, 1887.

Application filed September 9, 1886. Serial No. 213,104. (No model.)

To all whom it may concern:

Be it known that I, GEORG FISCHER, manufacturer, a subject of the King of Bavaria, and a resident of Nuremberg, in the Kingdom 5 of Bavaria, German Empire, have invented some new and useful Improvements in Plays with Rotating Gigs, of which the following is a specification.

My invention relates to improvements in 10 gigs, and the purpose of it is to move figures by the rotating of a gig.

The object of my invention consists in an 15 elastic friction-wheel fixed in a suitable frame, with a gig rotating on a step-bearing. The 20 rotating gig is held by this step-bearing in a correct distance from the elastic friction-wheel, so that the latter revolves by the rotating gig. The friction-wheel is fastened onto its axle, and the latter is in connection with figures, 25 which are automatically moved or turned by the rotation of the axle.

Figure I of Sheet I shows a side view of the 30 toy with two boxers, which shall be moved. The gig is taken away in this figure. Fig. II shows a vertical section through A B of Fig. I, the gig being in its place. Fig. III shows a horizontal section through C D of Fig. I, the gig being taken away. Figs. IV and V of Sheet II show a modification of this toy in 35 which the figure (a bear) is not moved to and fro as in Sheet I, but only turned round its axle. Both figures show vertical sections. In Fig. V the figure is taken away from the toy.

First, the arrangement, Sheet I, shall be de- 40 scribed.

In Fig. I a box-shaped casing, c, is placed on a foot-plate, a, by the supports b b, and is provided with two partition-walls, f and g. A rotating axle, r, provided with a crank, h, 45 is set up on the foot-plate a and placed in the casing c. On axle r sits fast a friction-wheel, f', which is provided with elastic wings f''. Besides the axle r with the annexed mechanisms, the foot-plate a bears a step-bearing, a', 50 destined for holding the rotating gig g in correct distance from the elastic friction-wheel f''. The crank h of the axle r is in connection with two figures (boxers X X) by means of the rods d d, and the levers v v', which oscillate if 55 so the crank h is turned. z z are the fulcrums

of these levers v v', which bear the boxer-figures, constructed as manikins. It is easy to see that by the rotation of the axle r these manikins are moved promiscuously. The rotation of this axle is gained by the gig and by 55 the following-described arrangement of it: The winged wheel f' f'' is adjustable on the axle r, and therefore wings f'' can be brought in close or more distant contact with the mantle surface of the gig by raising or lowering wheel 60 f' f'' on axle r. By this means velocity of rotation that has to be transmitted can be regulated in the simplest way according to liking. The wings of wheel f' can be of different materials and constructions. If, now, the gig g 65 has been made rotating in the well-known manner, by using a piece of cord it is set upon the step-bearing a', and now it transmits its rotary motion to the elastic wings f'', that lie against the surface of the gig. By this, as is 70 easy to understand, the boxers X X are moved. The gig g is held in correct position by the step-bearing a'.

The best and most advantageous way of 75 transmitting the motion is to provide wheel f' with wings f'', made of bird's feathers, Figs. I to IV, for they lay themselves closest to the surface of the gig and have a considerable amount of elasticity and adhesion. Instead of these radially-inserted bird's feathers, wings 80 made either of elastic thin chips, (of wood,) strips of paper, leather, or india-rubber, &c., can be used, as is exemplified in Fig. V. This elastic friction-wheel can likewise be used without wings, and in such a case it is made 85 in the shape of a bell, or ring, or cylinder, or ball, &c., and the frictional surface, (the surface coming in contact with that of the gig,) consists then of as thin and elastic a material as possible. 90

The gig g may be of any construction or shape whatever, or it may be one of the well-known musical (humming) gigs.

Figs. IV and V show a modification of this 95 toy. The only difference consists in the movement of the figure. In this modification, Figs. IV and V, the figure (a bear) is not moved to and fro, but it is only turned round itself. Naturally the axle r is not provided with a crank on its end, but only with a central top, 100

upon which the figure is set up by the hollow cylinder *y*, Fig. IV. The other mechanisms and movements of the gig *g* and of the axle *r* are the same.

- 5 All kinds of figures can be set in motion by this toy, and are made to perform the most comical motions.

What I claim, and desire to secure by Letters Patent of the United States, is—

- 10 1. The combination of a gig rotating on a step-bearing with an axle provided with a friction-wheel and figures moved by this axle, for the purpose as described.

2. The friction-wheel *f'*, with the elastic wings *f''*, in combination with the rotating gig held by the step-bearing *a'*, and the figures moved by the axle of the friction-wheel, for the purpose as described. 15

In witness whereof I have hereunto set my hand in presence of two witnesses.

GG. FISCHER.
